(57) **CLAIM**

The ornamental design for a transaction card, as shown and described.

DESCRIPTION

FIG. 1 is a front perspective view of a transaction card showing our new design;

FIG. 2 is a front view thereof;

FIG. 3 is a rear view thereof;

FIG. 4 is a top view thereof;

FIG. 5 is bottom view thereof; and,

FIG. 6 is a right side view thereof, the left side view being a mirror image of the right side view.

The broken lines shown in the figures are for illustrative purposes only and form no part of the claimed design. The bolded dash-dot-dash lines indicate boundaries of the claimed subject matter while all other broken lines illustrate unclaimed portions of the design.
